Lacy & Lacy, Attorney.

UNITED STATES PATENT OFFICE.

WILLIAM T. PLOWHEAD, OF MIDDLETON, IDAHO.

VISE-CLAMP.

1,288,178.

Specification of Letters Patent. Patented Dec. 17, 1918.

Application filed March 19, 1918. Serial No. 223,424.

To all whom it may concern:

Be it known that I, WILLIAM T. PLOWHEAD, a citizen of the United States, residing at Middleton, in the county of Canyon 5 and State of Idaho, have invented certain new and useful Improvements in Vise-Clamps, of which the following is a specification.

This invention relates to devices adapted 10 to be held between the jaws of a vise or like implement to hold pipes, rods and like objects in position while being threaded, filed or otherwise manipulated, and has for one of its objects to simplify and improve 15 the construction and increase the efficiency and utility of devices of this character.

Another object of the invention is to provide a device of this character which may be adapted to hold pipes, rods or like objects 20 of varying sizes, and which may also be employed for holding headed bolts while being threaded or otherwise acted on.

With these and other objects in view, the invention consists in certain novel features 25 of construction, as hereinafter shown and described and then specifically pointed out in the claims; and in the drawings illustrative of the preferred embodiment of the invention—

30 Figure 1 is a side elevation of a portion of a vise with one of the improved devices held between its jaws.

Fig. 2 is an end elevation of the vise and a side elevation of the attachment.

35 Fig. 3 is an enlarged perspective view of one of the coacting members of the improved device.

Fig. 4 is a detached perspective view of the other coacting member of the improved 0 device.

Fig. 5 is an enlarged transverse section on the line 5—5 of Fig. 2, illustrating the arrangement of one of the pipe or rod holding portions of the device.

Fig. 6 is a transverse section on the line 6—6 of Fig. 2 illustrating the construction of one of the bolt head holding portions of the improved device.

The improved device comprises coacting jaw or body members 10—11, preferably semi-circular in outline or arched, and with their confronting faces adapted to be held in parallel relation. One of the members, for instance the member 10, is provided at one end with a projection 12 having a lon-

gitudinally directed slot 13. The member 12 extends about one-half of the width of the member 10 as shown in Fig. 3. The member 11 is provided with a projection 14 extending about one-half of the width of the member 11 in opposite relation to the lug 12, so that when the members 10—11 are disposed in position with their confronting faces in parallel relation the inner face of the lug 12 will bear against the outer 65 face of the lug 14. A clamp bolt 15 extends through the slot 13 and an aperture in the lug 14, and is held in position by a clamp nut 16. By this means the members 10—11 are hingedly united at one end, and adjustable toward and away from each other within the range of the length of the slot 13. The members 10—11 may thus be maintained in parallel relation within the range 70 of the slot 13. Formed in the confronting faces of the members 10—11 are radially directed recesses 17—18, the bottoms of the recesses being serrated or roughened to increase the grip upon any object disposed in the recesses. Each of the recesses 17 is 75 opposite one of the recesses 18, the recesses 80 coacting to enable the members 10—11 to be gripped against a pipe, rod or like object, and firmly hold the latter in position when the jaws 19—20 of the vise are set up by 85 actuating the handle lever 21 of the vise. Formed in the confronting faces of the members 10—11, preferably between the recesses 17, are other recesses 22 conforming to the stock portion of a bolt or screw, enlarged 90 at their inner ends as shown at 23 to receive the head of the screw or bolt. The member 11 is provided with a similar series of recesses 24 and enlarged at their inner ends as shown at 25. The recesses 22—24 95 and their enlarged terminals 23—25 are designed to receive and support the stock and the enlarged head portions of bolts or screws, to hold the latter in position when the vise jaws are closed against the members 10—11. 100 The recesses 17 are of varying sizes to correspond to different sizes of pipes or rods, while the recesses 22—24 are likewise varied in size to enable bolts or screws of various sizes to be held in position. The outer faces 105 of the members 10—11 are preferably inclined or sloped away from their inner edges, as represented more particularly in Figs. 1, 5, and 6, so that an object held between the members 10—11 may be acted 110

upon by a file or other implement without interference from the adjacent faces of the holding members.

By forming the body members in arched shape, the ends of the vise jaws may be caused to grip the body members at spaced points, thus leaving an opening between the inner faces of the body members and the upper faces of the jaws of the vise, as shown in Fig. 2. By this means portions of the object which is held is exposed at each side of the gripping members, and can be thus readily acted on by a file or other instrument without interference from the vise jaws or other parts.

The improved device is simple in construction, can be manufactured at small expense, and of any required material, and is

automatically adjustable to objects of various sizes, and will firmly grip the object in any desired position, or at any required angle relatively to the jaws of the vise.

Having thus described the invention, what is claimed as new is:

A vise clamp comprising coating body members arched in outline, one of said body members having a slotted projection and the other body member having an aperture, and a clamping means operating through the slot and the aperture, whereby the body members may be gripped between the jaws of a vise at spaced intervals to provide an unobstructed opening between the vise engaging points and the body members.

In testimony whereof I affix my signature. 35

WILLIAM T. PLOWHEAD.
